Patented Aug. 23, 1921.

UNITED STATES PATENT OFFICE.

LEWIS H. SHIPMAN, OF BOSTON, MASSACHUSETTS.

TROLLEY-SHOE.

1,388,528.

Specification of Letters Patent.

Patented Aug. 23, 1921.

Application filed July 18, 1918. Serial No. 245,491.

To all whom it may concern: Be it known that I, LEWIS H. SHIPMAN, a citizen of the United States, and resident of Boston, county of Suffolk, and State of Massachusetts, have invented an Improvement in Trolley-Shoes, of which the following description, in connection with the accompanying drawings, is a specification, like letters on the drawings representing like parts.

My present invention is an improved sliding shoe for electrical transmission from a trolley wire to a vehicle or car and the object of my invention is to improve and perfect such trolley shoes. The advantages of a sliding shoe, as distinguished over a rotating wheel, are numerous and well known, employing a conducting member with a relatively long contacting surface which gives more efficient conductivity, eliminates the wearing of a constantly rotating member on its axles or bearings, is capable of long use, and is economical. However, the use of sliding

shoes in practice has been restricted because of certain practical difficulties, such as keeping the shoe in proper contact with the wire, and difficulties in providing a device which would slide in either direction upon wearing. My present invention obviates the difficulties heretofore experienced in sliding shoes of this type and I have devised a novel form of shoe which is of extremely simple construction, economical to build, apply, and most efficient in use, furthermore being capable of interchangeability while also being equally efficient in sliding movement in either forward or backward directions and at all times being readily retained in contact with the trolley wire. In my present invention I have eliminated undue weight, springs, or other attachments and have devised a practicable trolley shoe which operates to automatically maintain the long sliding wire-engaging portion of the shoe on the wire during either forward or backward movement of the trolley harp or car.

In carrying out my invention I provide a trolley harp and a shoe supported thereby with pivotal connection from the harp to the shoe at a point substantially at the extreme end of the long wire-engaging portion, forming two such wire-engaging portions on either side of the shoe and in planes

intersecting each other at a point removed from the pivot, uniting said planes at the pivot end by a curved line concentric with said pivot. This enables the shoe to be normally positioned in a substantially vertical plane while suspended from the harp before contact with the trolley wire and when first positioned in contact with the trolley wire. In this position the shoe will be automatically swung into proper wire-engaging position, either for forward or backward movement of the harp or car, simply by the forward or backward movement of the harp or car, such action serving to rock the shoe on the concentric wire-engaging portion and swing said shoe into proper position for its efficient operation with either of the long wire-engaging portions in contact with the wire with no tendency on the part of the shoe to overthrow. My trolley shoe is therefore at all times in position for either forward or rearward movement of the car with equal facility or efficiency without danger of the shoe "jumping" off the wire. As in practice the shoe would ordinarily be used principally for forward movement it is a further advantage of the present construction to enable the shoe to be reversed in the harp so that wear on each side may be utilized for the forward travel where the greatest wear goes, thus doubling the life and usefulness of my shoe.

Referring to the drawings illustrating the perfect embodiment of my present invention,

Figure 1 is a side view of a fragmentary portion of a trolley pole, the trolley harp attached thereto and my novel form of shoe in this normally suspended position;

Fig. 2 is a similar view showing the position of the shoe on the wire during the forward movement of the car with the trolley harp and pole at the usual rearwardly extending angle;

Fig. 3 is a similar side view showing the shoe in proper position on the wire when the car is moved backwardly;

Fig. 4 is a cross-sectional view on the line 4-4 on Fig. 2; and

Fig. 5 is a longitudinal cross-sectional view through the trolley shoe.

As shown in the drawings I have indicated the upper portions of the trolley pole which is held upwardly by a spring at its

95

100

105

110

base maintaining the pole in a yielding upward position, as is customary. The upper end of the trolley pole 1 is reduced in diameter as indicated at 2 and receives the hole 3 low shank portion 4 of the trolley harp 3, said harp having the upwardly extending arms 5 and 6, and the loop 7 to which the trolley cord is attached is also shown. The end portions of the arms 5 and 6 are enlarged slightly as shown at 8 with a hub 9 perforated to receive the axle 10 on which the trolley shoe 12 is pivotally mounted. I prefer to also provide a bushing in two parts 13 and 14 as clearly indicated in Fig. 4. Preferably this bushing is of suitable conducting material and may be employed, therefore, to carry the current from the shoe through the bushing to the harp. By having this bushing in two parts the current is divided and conducted equally through the arms 5 and 6. This relieves the pivot 10 of current carrying and therefore I may make the pivot of less conductivity than where the current is transmitted through the pivot, although the latter method may be employed whenever considered advisable. The pair of cotter pins 15-16 hold the axle 10 in position, said bushings preferably extending slightly beyond the hubs 9 of the arms 5 and 6 at each side of the harp and having V-shaped recesses 17, 17 therein through which the cotter pins are fitted so that the bushings on the axle are thus retained in assembled position.

The trolley shoe 12 is formed with its wire-engaging groove substantially in three sections or lengths, the relatively long straight wire-engaging portions for operating contact during either forward or rearward movement, being indicated at 20 and 21 and these substantially straight grooves being united by the curved section 22 concentric with the axis of the pivot 10. These grooves are of approximately equal depths, the flanges or sides 23 extending entirely around the shoe and grooves to the extreme rear portion 24, the numbers 20, 21, and 22 indicating the base of the grooves and the wire-engaging surfaces of the shoe. The thickness of the metal which preferably is of any suitable wear-resisting and electrically conducting material, between the base of the grooves and the recess for the pivot 55 may be proportioned for length of service and wearability as may be desired, it being possible to use my shoe until the metal is worn down on one groove almost entirely to the pivot and then to reverse the shoe and use the other groove for the forward moving portion, the rearwardly moving service to which the shoe is subject being relatively slight and intermittent. I may also lighten the shoe by coring the recess 25 when deemed 60 65 advisable. In the operation of my improved

sliding shoe it is easily and quickly assembled upon the harp, and when the harp and trolley pole are elevated to position of contact with the trolley wire 30, the shoe is normally pendant presenting the curved or 70 wheel-like grooved portion 22 for initial contact with the trolley wire and with the shoe in this position it is thus ready for instant and automatic operation through movement of the car into the position for 75 its proper and efficient use during the forward propulsion of the car as shown in Fig. 2, or for backward movement of the car as shown in Fig. 3. The instant that the car moves in either direction, the friction 80 between the shoe and wire automatically rocks the shoe on the circular grooved portion 22 until the shoe is swung with the tangential straight portions 20 or 21 respectively, into contact with the wire, continued moving of the car maintaining the shoe in this position with the long straight surface of the shoe in sliding contact with the wire and in position for most efficient conductivity. Moreover the shoe is thus maintained with a degree of yielding or resilient 85 action due to the lifting of the weight of the lower portion of the shoe, because of its eccentric mounting. This function of yielding is important as it enables the shoe to 90 follow the sinuosities in the trolley wire due to differences in height, yield, swing, or sag of the wire, retaining the shoe in wire-engaging position and very largely eliminating the danger of the shoe "jumping" off 95 the wire. When one groove is worn the shoe may be instantly reversed in position and the unworn grooved portion brought into use, by simply withdrawing one cotter pin and removing the axle, reversing the shoe 100 and replacing the axle. Although I prefer to use the bushing as the conductor, as above described, because of the slight wearing upon the pivot, the axle may be made of electrical conducting material, if desired, 105 although it is possible also on account of the slight oscillation and wear, to utilize the contact sides of the shoe, with the arms 5 and 6, as indicated at 26 and 27 taking the current directly therethrough and thence 110 from the harp by the wire (not shown) to the car.

My invention is further described in the form of claims as follows:

1. A sliding trolley shoe of the kind described, comprising two wire-engaging surfaces extending in divergent planes connected at the point of greatest divergence by a wire-engaging arc shaped surface.

2. A sliding trolley shoe of the kind described, comprising a trolley harp, a contact member pivoted to said harp, wire-engaging grooves extending at an angle relatively to each other and being farthest separated substantially opposite the pivot, and a wire- 130

engaging groove formed in an arc substantially concentric with said pivot, and uniting said wire-engaging grooves.

3. A sliding trolley shoe of the kind described, including a trolley harp, a pivotal mounting for the shoe eccentric to its center of gravity, two straight wire-engaging grooves extending longitudinally and diverging from a common point with their 10 point of greatest divergence substantially opposite the axis of the pivot and a curved wire-engaging groove uniting said straight grooves and extending around the pivot, whereby the shoe will normally hang vertically 15 from its pivot with the curved portion upward for initial wire-engagement and in position to bring either straight groove into wire-engaging contact by the movement of the trolley harp either forwardly or backwardly.

4. A sliding trolley shoe of the kind described having approximately the shape of one half of a trolley wheel, extended from the ends of the arc by flat surfaces lying in approaching planes, said shoe being pivoted 25 at substantially the same point at which a complete trolley wheel having the same arc would be pivoted.

5. A sliding trolley shoe of the kind described, comprising a trolley harp, a substantially triangularly shaped sliding shoe pivoted to said harp, permitting partial rotative movement and a counterbalancing weight in said shoe to cause the shoe to normally hang on its pivot in a predetermined 30 35 position.

In testimony whereof, I have signed my name to this specification.

LEWIS H. SHIPMAN.
